UNITED STATES PATENT OFFICE.

CHARLES P. GRIMES, OF SYRACUSE, NEW YORK, ASSIGNOR TO PEDWYN BALANCER CORPORATION, OF SYRACUSE, NEW YORK, A CORPORATION OF NEW YORK.

SAFETY LOCK FOR COUNTERBALANCING DEVICES.

Application filed January 6, 1927. Serial No. 159,284.

This invention relates to winding drums which are actuated in one direction by a spring and has for its object a particularly simple and efficient safety lock for locking the drum from turning movement under the influence of the weight or load on the cable winding on the drum, if the drum spring breaks.

The invention consists in the novel features and in the combinations and constructions hereinafter set forth and claimed.

In describing this invention, reference is had to the accompanying drawings in which like characters designate corresponding parts in all the views.

Figure 2 is a side elevation of a counterbalancing device embodying my invention.

Figure 1 is a sectional view on line 2—2, Figure 2.

I have here shown my invention as embodied in a counterbalancing device or a device used for counterbalancing tools such as electric drills and the like although it is equally applicable in any machine having a spring wound drum regardless of the character of the load carried by the cable winding on the drum.

The illustrated embodiment of my invention comprises, generally, a spring wound drum and a spring for winding the drum, a lock normally in ineffective position and having means for moving it into effective position to lock the drum from turning if the spring breaks and means for normally holding the lock in ineffective position, said means being connected to the drum spring and held thereby under the tension of the drum spring in its normal position where it holds the lock in ineffective position, all whereby if the drum spring breaks, the lock is free to move into engagement with the drum and hold it from turning.

1 designates the drum which is here shown as mounted upon a spindle 2 to rotate about the same, the spindle being mounted in a suitable support as a casing 3.

4 is the drum spring coiled about the axis of the spindle 2 and connected at its outer end

to the drum and at its inner end to a spring abutment 5 also mounted on the spindle 2 to rotate relatively thereto and also rotatable in a central bearing 6 in a detachable outer wall 7 of the casing, the abutment extending to the outside of the casing in order to be turned to tension the spring.

8 is the load supporting cable winding on the drum.

The casing 3 is provided with means on the upper side thereof for connection to an overhead support, this means being here shown as a lug 9 and link 10 pivoted to the lug. The cable 8 extends out through a tangential outlet 11 on the lower side of the casing.

The supporting means or lug 9 and link 10 are located in a vertical line between vertical lines, one passing through the axis of the drum and the other lengthwise of the outlet for the cable. The casing and drum construction and relative arrangement of these parts forms no part of this invention.

The abutment 5 is shown as a sleeve mounted on the spindle 2 and the free end of the spindle is supported in this abutment as the abutment is supported in the bearing 6. The outer end of the spring is secured to a lug 12 within the drum.

The lock is normally held from moving into locking position by the tension of the spring 4 acting through a detent coacting with the lock. The lock is here shown as a spring pressed bolt or rod 13 carried within the casing 3 by the removable cover plate 7 thereof and being here shown as slidable in lugs 15, 16 on the inner side of said cover plate 7 and as movable vertically so that its lower end projects into notches in the drum or into spaces between lugs 17 on the front side of the drum. The bolt or rod 13 is spring pressed by a spring 18 interposed between the lug 16 and a suitable shoulder on the hub of the rock arm 19 mounted on the rod. The bolt is held in its retracted position against the action of the spring 18 by a

detent rotatable with the spring abutment, 95 this detent being here shown as any one of a

plurality of teeth 20 provided on a flange 21 on the abutment 5, the flange being located on the outside of the case 3 or wall 7 thereof and coacting with the rock arm 19 which extends out through an opening 23 in the wall 7. The abutment 5 is also provided with a wrench hold 24 at its extreme outer end by means of which it can be turned to tension the spring. The rock arm 19 serves to hold the abutment from retrograde movement, that is, to hold the spring from untensioning. The spring 18 is anchored at its ends to the lug 16 and the rock arm 19 on the hub thereof so that the spring also acts as a torsion spring to rock the shaft or bolt in one direction or the other. Preferably it rocks the shaft in such direction to move the arm 19 toward its position assumed when the arm is engaged with its detent 20.

20 The removable cover plate 7 is held in position by suitable screws 25 and also it is formed with a suitable opening 28 normally closed by a cover 29 held in position by screws 30.

25 During the tensioning of the spring, the rock arm 19 is swung laterally outwardly out of engagement with the teeth 20 and when the spring is tensioned, it is again swung laterally inwardly into engagement with the teeth. The rock arm is keyed to the bolt or rod 13 so that the bolt or rod also rocks during this operation.

In operation, after the spring has been tensioned, the parts are in their positions shown in Figure 2. If, however, the drum spring 4 breaks, the holding force on the locking bolt 13 is removed so that the spring 18 is free to react and force the bolt into engagement with the drum or between the lugs 17 and thus hold the drum from turning under the influence of the weight or load on the cable 8. Hence, the liability of injuring workmen by the falling of the load on the cable if the spring breaks is entirely eliminated.

45 What I claim is:

1. In a device of the class described, the combination of a winding drum, a spring acting on the drum to wind it and a lock for holding the drum from turning, the lock being normally in ineffective position, means tending to move it in effective position to lock the drum from turning and means actuated by the spring normally holding the lock out of effective position whereby if the spring breaks the lock moves into effective position.

2. A device of the class described comprising a winding drum, a spring acting on the drum to wind it, a spring pressed lock for holding the drum from turning movement, the lock being normally in ineffective position, a detent coacting with the lock for holding the lock in its ineffective position, the detent being connected to the drum spring to be actuated thereby.

65 3. A device of the class described comprising a support, an axle mounted in the support, a winding drum mounted on the axle to rotate about the same, a spring abutment rotatably mounted on the axle, a coiled spring connected at its inner end to the spring abutment and at its outer end to the drum, a lock carried by the support and movable into engagement with the drum to hold it from movement, the lock being normally in its inoperative position, a spring tending to move it into locking position and means connected to the spring abutment and coacting with the lock to hold it in its normal position, all whereby if the coiled spring breaks, the lock is free to move into locking engagement with the drum.

4. A device of the class described comprising a support, an axle mounted in the support, a winding drum mounted on the axle to rotate about the same, a spring abutment rotatably mounted on the axle, a coiled spring connected at its inner end to the spring abutment and at its outer end to the drum, a lock carried by the support and movable into engagement with the drum to hold it from movement, the lock being normally in its inoperative position, a spring tending to move it into locking position and means connected to the spring abutment and coacting with the lock to hold it in its normal position, all whereby if the coiled spring breaks, the lock is free to move into locking engagement with the drum.

5. A device of the class described comprising a winding drum, a spring acting on the drum to wind it, a spring pressed lock for holding the drum from turning movement, the lock being normally in ineffective position, and an abutment for one end of the spring, a detent coacting with the lock and connected to said spring abutment and coacting with the lock to hold the lock in its ineffective position, the lock also normally holding the detent and the abutment from movement by the drum spring and being movable out of engagement with the detent to permit winding of the spring.

6. A counterbalancing device comprising a support, a spindle mounted in the support, a winding drum mounted on the spindle to rotate about the same, a spring abutment mounted on the spindle within the drum, a coiled spring fixed at its outer end to the drum and at its inner end to the abutment, the abutment being rotatable about the spindle to tension the spring, a lock carried by the support and movable into engagement with the drum to hold it from turning, a spring normally pressing the lock into effective position, a detent rotatable with the spring abutment and coacting with the lock to hold the lock in its retracted position.

7. A counterbalancing device comprising a

support, a spindle mounted in the support, a winding drum mounted on the spindle to rotate about the same, a spring abutment mounted on the spindle within the drum, a coiled spring fixed at its outer end to the drum and at its inner end to the abutment, the abutment being rotatable about the spindle to tension the spring, a lock carried by the support and movable into engagement with the drum to hold it from turning, a spring normally pressing the lock into effective position, a detent rotatable with the spring abutment and coacting with the lock to hold the lock in its retracted position, the portion of the lock 10 acting with the detent being shiftable out of the path of the detent to permit turning of the abutment to tension the spring.

8. A device of the class described comprising a support, a spindle mounted in the support, a winding drum mounted on the spindle to rotate about the same, a spring abutment rotatable about the spindle, a coiled spring connected at its outer end to the drum and at its inner end to the abutment, a lock 20 comprising a bolt carried by the support at one side of the drum, a spring acting on the bolt to press it into engagement with the drum to hold the drum from turning, a detent mounted on the spring abutment, a rock arm 25 mounted on the bolt and coacting with the detent, the detent holding the bolt in its retracted position.

9. A device of the class described comprising a support, a spindle mounted in the support, a winding drum mounted on the spindle to rotate about the same, a spring abutment rotatable about the spindle, a coiled spring connected at its outer end to the drum and at its inner end to the abutment, a lock 30 comprising a bolt carried by the support at one side of the drum, a spring acting on the bolt to press it into engagement with the drum to hold the drum from turning, a detent mounted on the spring abutment, a rock arm 35 mounted on the bolt and coacting with the detent, the detent holding the bolt in its retracted position, the rock arm being movable laterally out of engagement with the 40 detent to permit turning of the spring abutment to tension the spring.

10. A counterbalancing device comprising a casing, a drum mounted in the casing, a load carrying cable winding on the drum, a spring mounted in the casing and connected 45 to the drum to turn it to wind the cable thereon, a lock in the casing normally out of operative position and movable into position to lock the drum from turning under the influence of the load if the spring breaks, the lock having 50 a portion extending outside of the casing and a detent located outside of the casing and coacting with said lock portion for holding the lock from movement into operative position, the spring being connected at one end 55 to the detent.

11. In a device of the class described, the combination of a winding drum, a spring coacting on the drum to wind it, a spring pressed lock for holding the drum from turning, the lock being normally in ineffective 70 position, and means operated by the coil spring to hold the lock from actuation by its spring.

12. In a device of the class described, the combination of a winding drum, a spring coacting on the drum to wind it, a spring pressed lock for holding the drum from turning, the lock being normally in ineffective position, and means operated by the coiled 75 spring to hold the lock from actuation by its 80 spring, the lock including a portion shiftable out of engagement with said means to permit winding of the coiled spring.

13. A counterbalancing device comprising a casing open at one side, and a removable 85 cover for the open side, a drum mounted in the casing, a load carrying cable winding on the drum, a coiled spring mounted in the casing and connected to the drum to turn it to wind the cable thereon, a lock normally 90 out of operative position and movable into position to lock the drum from turning under the influence of the load, the lock having means for moving it into effective position, and means controlled by the coiled spring to 95 normally hold the lock from movement into operative position, said lock being carried by the cover.

14. A counterbalancing device comprising a casing open at one side, and a removable 100 cover for the open side, a drum mounted in the casing, a load carrying cable winding on the drum, a coiled spring mounted in the casing and connected to the drum to turn it to wind the cable thereon, a lock normally out 105 of operative position and movable into position to lock the drum from turning under the influence of the load, the lock having means for moving it into effective position, means controlled by the coiled spring to normally hold the lock from movement into operative position, said lock being carried by the cover, the lock holding means having a portion located outside of the cover and the lock including a portion extending through the 110 cover to the outside thereof coacting with said holding means.

15. A counterbalancing device comprising a casing open at one side, and a removable 120 cover for the open side, a drum mounted in the casing, a load carrying cable winding on the drum, a coiled spring mounted in the casing and connected to the drum to turn it to wind the cable thereon, a lock normally out 125 of operative position and movable into position to lock the drum from turning under the influence of the load, the lock having means for moving it into effective position, means controlled by the coiled spring to normally hold the lock from movement into oper- 130

ative position, said lock being carried by the cover, the lock holding means having a portion located outside of the cover and the lock including a portion extending through the cover to the outside thereof and coacting with said holding means, and said portion of the lock being movable out of engagement

with the holding means to permit winding of the spring.

In testimony whereof, I have hereunto signed my name, at Syracuse, in the county of Onondaga, in the State of New York, this 21st day of December, 1926.

CHARLES P. GRIMES.
